UNITED STATES PATENT OFFICE.

CHARLES DABNEY, OF WINNSBORO, TEXAS.

FEED-MIXING MACHINE.

No. 923,248.

Specification of Letters Patent.

Patented June 1, 1909.

Application filed January 20, 1908. Serial No. 411,707.

To all whom it may concern:

Be it known that I, CHARLES DABNEY, citizen of the United States, residing at Winnsboro, in the county of Wood and State 5 of Texas, have invented certain new and useful Improvements in Feed-Mixing Machines, of which the following is a specification.

This invention relates to an improvement 10 in mixing machines and more particularly to a machine for mixing stock food.

Cotton seed hulls mixed with a small percentage of cotton seed meal is extensively used in this country as a stock food and the 15 principal object of the present invention is the provision of a simple and compact machine for mixing stock food of this character, by the use of which the ingredients which are to form the mixture may be mingled in the 20 proper proportions, thoroughly mixed, and then conveyed to any desired point.

Other objects of the invention will be apparent from the detailed description hereinafter when read in connection with the 25 accompanying drawing forming a part thereof, wherein a convenient embodiment of the invention is shown.

In the drawing is illustrated a side elevation of the improved mixing machine.

Referring now more particularly to the 30 drawings, A designates a frame of any suitable construction which is arranged to support the several parts of the improved mixing machine.

B, B designate a pair of weighing hoppers which are side by side and are suspended from scale beams C, C of any suitable construction, which are pivotally supported in the top of the frame A, A. The lower ends 40 of the weighing hoppers B, B are provided with hinged bottoms b, b which are normally held in closed positions by means of latches of any suitable type, which latches are of such a construction that they may be at any 45 time released by the operator to permit said bottoms to fall and discharge the contents of the hoppers. Arranged side by side within the frame A and positioned beneath the weighing hoppers B, B are a pair of mixing 50 drums D, D, the lower ends of which are provided with discharge spouts d which communicate with a conveyer casing E which extends transversely of the frame A and within which is journaled a shaft E' which 55 carries a screw or other suitable conveyer e.

Communication between the interior of the mixing drums D, D and the discharge spouts d, d thereof is normally closed by means of a pair of slides d', d' which normally lie across the upper ends of said spouts but which may 60 at any time be withdrawn to permit the material within the mixing drums to be discharged into the conveyer casing E. Journaled within the frame A and extending transversely thereof is a shaft F which passes 65 axially through the mixing drums D, D. Secured to said shaft within each of the mixing drums D, D are a pair of collars f, f from which extend a plurality of radially disposed arms, the outer ends of which are provided 70 with mixing blades or paddles f' of any desired type, the arms on the two collars being preferably arranged in staggered relation. While the shaft F has been described as provided with two sets of mixing arms, it is 75 obvious that any other arrangement of mixing arms or blades may be utilized. Communication is afforded to the interior of the mixing drums D, D by means of hoppers d², d² which are secured to the tops thereof. 80 The walls of the hoppers d², d² are inclined and the outer wall of each of said hoppers is of such a height and is so positioned with reference to the weighing hopper positioned thereabove, that when the bottom of said 85 weighing hopper is released it will while in an inclined position contact with said outer wall and constitute therewith a chute for directing the material from said weighing hopper into said mixing drum. The inner 90 wall of each of the hoppers of said mixing drums is positioned slightly beyond the inner wall of the weighing hopper positioned directly thereabove, so that none of the material from said weighing hopper when the 95 bottom thereof is released will be deflected over the top of said inner wall.

G designates a power shaft which is journaled in the upper portion of the frame A and extends transversely thereof, to which rotation is designed to be imparted from any suitable source of power. The shaft G is connected through the medium of a belt or other suitable gearing with the shaft F which carries the mixing arms, which shaft is in turn connected through the medium of a belt or other suitable gearing with the conveyer shaft E'.

Mounted in the top of the frame is a suitable spout B' which is provided with branches leading to the upper ends of the 110

weighing hoppers B, B, through which the material is designed to be introduced into said hopper.

In the use of the device, different portions of cotton seed hulls and cotton seed meal, a comparatively small amount of the latter being used, are fed to any desired extent to the hoppers B, B through the chute B' and the doors of the hoppers are then actuated to permit the material to pass into the mixing drums D D, the doors of the hoppers B B being immediately closed so that the hoppers can be refilled while the previous charges are being mixed. The material is allowed to remain in the mixing drums until the cotton seed hulls and cotton seed meal or other ingredients have been thoroughly commingled, after which time, the slides d' d' are manipulated to permit the thoroughly mixed material to pass to the conveyer E by which it may be carried to any desired point.

While I have described two weighing hoppers and two mixing drums which are used in conjunction therewith, it is obvious that only one or any number of said hoppers and mixing drums may be utilized if desired.

I do not desire to limit myself to the pre-

cise form and construction shown in the drawings as it is obvious that many minor changes might be made thereto without departing from the spirit of the invention as defined in the appended claims.

I claim:

In a device of the character described, a frame, a weighing hopper suspended therein and provided with a hinged bottom, and a mixing drum positioned below said weighing hopper and provided with an inlet hopper having an inclined side wall adapted to be engaged by the hinged bottom of the weighing hopper when the same is released, a conveyer casing positioned below said mixing drum and communicating therewith, a conveyer in said casing, and a valve for controlling the passage of material from said mixing drum to said conveyer casing.

In testimony whereof I have signed my name to this specification in the presence of two subscribing witnesses.

CHARLES DABNEY.
